UNITED STATES PATENT OFFICE.

JOHN ORBIK, OF HURLEY, WISCONSIN.

RAILROAD-SWITCH.

1,105,996.

Specification of Letters Patent. Patented Aug. 4, 1914.

Application filed February 21, 1914. Serial No. 820,226.

To all whom it may concern:

Be it known that I, JOHN ORBIK, a citizen of the United States, residing at Hurley, in the county of Iron and State of Wisconsin, have invented certain new and useful Improvements in Railroad-Switches; and I do hereby declare the following to be a full, clear, and exact description of the invention, such as will enable others skilled in the art to which it appertains to make and use the same.

This invention relates to railroad switches and has for one of its objects the provision of means for yieldingly holding the switch points in either of their respective positions, and the provision of means for the automatic movement of the same so that rolling stock of the road may pass through the same when the switch is closed to the track upon which the rolling stock is traveling.

A further object of this invention is the provision of means for maintaining the rails of the track at the switch in their relative parallel relation to each other in a manner for obviating the necessity of numerous web blocks which have to be used in constructions of this character.

A still further object of this invention is the construction of a switch consisting of few parts, efficient in purposes and which can be repaired readily and at a nominal cost.

These and other objects will more fully appear and the nature of the invention will be more clearly understood by the construction, combination and arrangement of parts thereof as described in the following specification, defined in the appended claims and illustrated in the accompanying drawings, in which,

Figure 1 is a top plan view of the switch and its component operating parts constituting my invention and illustrating the same as it appears in operative position. Fig. 2 is a transverse view of the switch taken on line 2—2 of Fig. 1 and looking in the direction of the arrows.

Like reference characters denote corresponding parts throughout the several views of the drawings in which 1 represents the usual ties upon which are mounted the main rails 2—2 and the switch rails 3—3. For maintaining the rails 2—2 and 3—3 in their normal parallel relation to each other and positioned between the alternate pairs of ties are tension devices comprising the

turn buckles 5 having screw threaded in the opposite ends thereof the oppositely extending rods 6 which rods are provided upon their free ends with the upwardly turned hook members 7 for engaging the outer base and web of the respective rails.

I desire to here state, that in view of the lack of space, and for the sake of clearness, certain of the parts of the switch mechanism have been slightly exaggerated, however, in practical use, the parts are to be proportionately correct.

Connected to the ends of the switch rails 3 are the switch points 9, the points being connected together and retained in their respective predetermined relation to each other by the arrangement of the web blocks 11 secured to each of the opposing faces of the points 9 in any suitable and efficient manner, the web blocks 11 being provided with apertured ears 12. The web blocks 11 are positioned at points between the remaining alternate pairs of ties and have connected thereto the transversely extending bars 13, which bars have provided upon the upper surface thereof the apertured ears 14 at points upon the bars 13 in order that the same may be pivotally connected to the ears 12 of the web blocks 11 through the means of the pivotal bolts or other suitable connections 15.

Positioned approximately at the extremity of the switch points 9 are arranged a pair of switch ties 10—10 spaced apart in the usual manner and between them there is positioned the foremost of the connecting bars 13. Upon the switch ties 10—10 and beneath the respective rails and switch points are the bearing plates 10' to provide anti-friction or smooth traveling surfaces for the switch points 9.

The cross bars 13 are each elongated and adapted to pass beneath the bases of the respective rails and to project for a distance beyond the outer sides of the rails, as shown at 16, the purposes of these extensions being for maintaining the switch points in strict vertical position and to prevent the wabbling or overturning of the tread surfaces of the switch points. The foremost cross bar 13 has one of its ends elongated and gradually increasing in dimensions to provide the switch rod 17, which has arranged upon the upper surface thereof and adjacent to but slightly removed from the outer side of the rail 3, the upwardly ex-

tending lug 18 through which and the rail 3 is adapted to extend the horizontal sliding pin 19 and surrounding the pin 19 and between the lug 18 and the opposing face 5 of the rail 3 is the compression spring 20 for normally bearing the lug 18 in an outward direction.

Arranged upon each of the switch ties and at a point sufficiently remote from the 10 track are the journals 22 secured to the switch ties by suitable fastening means as indicated at 23, and rotatably mounted within the journals 22 is the horizontal shaft 24 provided intermediate of its ends 15 with the elongated crank portion 25. The shaft 24 is further provided with the angularly disposed switch lever 26 provided at the extremity thereof with the weighted head 27. Longitudinally arranged upon 20 one of the switch ties 10 and at opposite points to the axis of the shaft 24 are the lugs 28 to provide locking means for the switch lever 26 when in either of its respective positions. Transversely arranged within 25 in the switch rod 17 and in proximity to the outer extremity thereof is the elongated slot 30 through which the crank 25 of the shaft 24 is designed to pass and travel therein, the crank 25 being yieldingly retained therein by the compression spring 31 arranged in the longitudinal bore 32 extending from the slot 30 outwardly to the end rod 17 and retained therein by the screw threaded adjusting screw plug 33. The switch rod 17 is 30 preferably formed in one piece of sufficient length and degree of flexibility to provide for the slight vertical movement of the outer end thereof occasioned by the crank 25. However, the switch rod may be 35 formed in two parts and pivotally connected together at any point between the lug 18 and the slide bar 37, if so desired.

Arranged upon the crank 25 and at either side of the switch rod 17 are the apertured heads 35 of the rods 36, these rods extending longitudinally at each side of the switch rod 17 in the direction of the track and having their free ends extending through the ears 36' of the slide bar 37 and retained in secured relation thereto by the adjustable nuts 38' screw threaded thereon. The slide bar 37 is adapted to pass through a second transversely arranged slot 39 for positioning one of its ears 36' at either side of the switch bar 17 and in the path of the rods 36, the slot 39 being somewhat restricted in length to that of the slot 30 and arranged in proximity thereto but between the slot 30 and the track. For maintaining the slide bar 37 60 normally against the end wall of the slot 39 in the direction of the track, and for also maintaining a constant opposed stress between the crank 25 and the slide bar 37 the compression springs 40 are provided, these 65 springs surrounding the rods 36 and hav-

ing their opposite ends bearing against the opposing faces of the heads 35 and the ears 36' respectively. The spring 31 and the springs 36 are positioned at the opposite sides of the crank 25 for yieldingly retaining the crank at a point approximately intermediate of the ends of the slot 30, the slot being of sufficient length for preventing contact of the crank 25 with either of the end walls thereof. The slot 39 is arranged 70 for permitting the slide bar 37 to normally engage the end of the same nearest the track but of sufficient length in the opposite direction for preventing the contact of the slide bar 37 with the outer wall of the slot 39. The compression spring 20 and the compression spring 31 co-act with each other and have a tendency to force the switch rod 17 in a direction outwardly from the track, while the compression springs 36 75 have a tendency to throw the bar 17 toward the track, but these springs, however, are of a suitable degree of strength for equalizing the opposing tendencies.

The operation of the switch is clearly obvious from the foregoing description and the construction sufficiently illustrated in the drawings to not require further detail description of the operation of the device. However, it is deemed expedient to note that 90 in the position of the switch points shown in Fig. 1 should a train pass out of the switch onto the main track the stress exerted upon the switch point by the flanges of the wheels of the rolling stock would obviously force 95 the rails in the opposite direction against the action of the spring 20 and the spring 31, whereupon after the passage of the rolling stock the points would be returned to their original position. Should the points be in 100 the opposite position the switch rod and points would be forced against the compression springs 36, the same also returning the switch rod and points to its former position 105 after the passage of the rolling stock.

Having thus fully described my invention, what I claim and desire to secure by Letters-Patent of the United States, is:

1. A switch mechanism, in combination with movable switch rails, means for retaining the switch rails in parallel relation, a switch rod associated with one of said retaining means, said switch rod being provided with elongated slots therein, a crank shaft for operating said switch rod, the crank of said shaft extending through one of said slots, and a spring within said switch rod for yieldingly supporting said crank within said slot.

2. A switch mechanism, in combination with movable switch rails, means for retaining the switch rails in parallel relation, a switch rod associated with one of said retaining means, said switch rod being provided with elongated slots therein, a crank shaft 125

- for operating said switch rod, the crank of said shaft extending through one of said slots, a spring within said switch rod for yieldingly supporting said crank within said slot, and springs arranged at each side of said switch rod coacting with the spring therein for yieldingly supporting said crank intermediately within said slot.
3. A switch mechanism, in combination with movable switch rails, means for retaining the switch rails in parallel relation, a switch rod associated with one of said retaining means, said switch rod being provided with elongated slots therein, a crank shaft for operating said switch rod, the crank of said shaft extending through one of said slots, a spring within said switch rod for yieldingly supporting said crank within said slot, springs arranged at each side of said switch rod coacting with the spring therein for yieldingly supporting said crank intermediately within said slot, and a cushion spring arranged upon said switch rod adjacent the rails.
- 25 4. A switch mechanism, in combination with movable switch rails, means for retaining the switch rails in parallel relation, a switch rod associated with one of said retaining means, said switch rod being provided with elongated slots therein, a crank shaft for operating said switch rod, the crank of said shaft extending through one of said slots, a spring within said switch rod for yieldingly supporting said crank within said slot, springs arranged at each side of said switch rod coacting with the
- spring therein for yieldingly supporting said crank intermediately within said slot, a cushion spring arranged upon said switch rod adjacent the rails, and a switch lever 40 for operating said crank shaft and said switch rod.
5. A switch mechanism, in combination with movable switch rails, means for retaining the switch rails in parallel relation, a 45 switch rod provided by the elongation of one of said retaining means, said switch rod having transversely arranged elongated slots therein, a crank shaft for operating said switch rod, the crank for said switch rod 50 extending through one of said slots, a slide bar extending through the other of said slots, actuating rods arranged upon said crank at each side of said switch rod, the free ends of said rods slidably connected 55 with said slide bar, a spring within said switch rod, springs arranged upon said actuating rods, a cushion spring upon said switch rod adjacent the rails, said springs coacting with each other to provide a resilient connection between said switch rod and said crank therethrough, and a switch lever for operating said rod and said crank.
- In testimony whereof I have signed my name to this specification in the presence of 60 two subscribing witnesses.

JOHN ^{his} X ORBIK.
